UNITED STATES PATENT OFFICE.

FRANS HENRIK AUBERT WIELGOLASKI, OF CHRISTIANIA, NORWAY.

REACTION TURBINE FOR WATER, WIND, STEAM, ETC.

Application filed September 3, 1919. Serial No. 321,314.

To all whom it may concern:

Be it known that I, FRANS HENRIK AUBERT WIELGOLASKI, subject of the King of Norway, and resident of Odins Gate 1, Christiania, Norway, have invented certain new and useful Improvements in Reaction Turbines for Water, Wind, Steam, Etc., of which the following is a specification.

The present invention relates to turbine 10 motors and more particularly to an improved motor wherein the pressure of the fluid (its static energy) rather than its velocity (its kinetic energy) is utilized to develop power.

15 In consequence of the utilization of the static energy of the fluid the turbine of the present invention has a high degree of efficiency as compared with other turbine motors. This is due probably to the fact that 20 speed of rotation of the turbine may be relatively low, the pressure of the fluid being constant and uniform so long as the head of fluid is maintained constant and the power at all times depending solely on the difference 25 in fluid pressure at the respective sides of the turbine.

To obtain these results I provide a turbine wheel having suitably shaped blades or vanes and I mount the wheel so as to be entirely 30 filled with the fluid at all times and to be in communication at all times at one side with fluid at one pressure and at the other side with fluid at relatively low pressure.

35 Considered more specifically the turbine wheel is so mounted that the fluid under excess pressure passes transversely across the wheel reacting first against the blades at one side of the wheel, and, because of the 40 shape of the blades, causing the wheel to be rotated, and then against the blades at the other side of the wheel, further rotating the wheel. Naturally, when the wheel rotates, fluid, the excess energy of which has been 45 consumed, is brought into the space between the blades back to the high pressure side, but as soon as it reaches this side the high pressure fluid reacts against the carried-back fluid and forces the same from between the 50 blades, further imparting rotation to the wheel. It will therefore be seen that in effect the high pressure fluid acts upon the fluid in the space between the blades in addition to itself acting upon the blades.

55 Since the turbine of this invention utilizes fluid pressure which of course is uniform

for the entire width of the head, several turbines according to this invention may be connected together or one turbine, the entire width of the head may be used. This is 60 not possible with the turbines heretofore known or with the methods heretofore used. The power of the turbine is further enhanced by causing the fluid to follow a course substantially tangential of the wheel before 65 it encounters the same.

My improvements are applicable to water, steam air or other fluids and while the following specification is directed for the most part to water turbines, it should not be understood that my invention is limited to the 70 same.

Several embodiments of my invention are illustrated in the accompanying drawings in which,

75 Figure 1 is a diagrammatic view of one embodiment of my invention, showing a water turbine.

Fig. 2 is a diagrammatic view showing my invention as applied to an air operated 80 turbine.

Fig. 3 is a view similar to Fig. 1 showing guiding blades on the high pressure side of the turbine wheel.

According to the present invention as illustrated in the drawings the turbine wheel B is mounted to rotate on a horizontal shaft and has a plurality of vanes or blades of suitable curvature arranged along the outside edge of a pair of discs or wheels. The 85 form of the invention shown in Figs. 1 and 2 is particularly adapted for use where large quantities of water have only a relatively low speed. Consequently, the turbine wheel B is preferably of sufficient length to extend 90 across the entire width of the body of water. The turbine is mounted in a chamber or conduit for the motive fluid, said conduit being provided with a diagonal wall whereby at one side of the turbine there is a canal S 100 diverging toward the upper surface of the body of water T with which it communicates, while at the other side the turbine wheel communicates directly with a body of water C the level of which is lower than the level 105 of the water T. In consequence of this arrangement the hydrostatic pressure in the canal S is greater than the hydrostatic pressure of the water at the other side of the wheel B. The water T and the water C are 110 separated by a wall or dam which preferably slopes toward the canal S forming with the

ledge from which the water T descends, a funnel shaped arrangement.

The excess pressure of the water in the canal S causes the water to be forced against the vanes or blades of the wheel B and to tend to cross through said wheel to the low pressure side of the turbine. The blades do not extend for the entire radius of the wheel but terminate approximately half way toward the axis of the wheel consequently providing a free space or chamber in the interior of the wheel B. The water T under excess pressure impinging upon the blades of the wheel B in its effort to pass to the low pressure side C causes the wheel to rotate, the water passing to the free space or chamber in the wheel and through the blades at the other side thereof to the low pressure water C. It will thus be seen that the static energy of a column of water passing through the canal S and bearing upon the vanes at each side of the wheel will cause the wheel to rotate with more or less power according to the difference between the low and high pressure water columns or heads. Where this difference is slight it is of course important that great quantities of water pass through the wheel in order to develop the necessary power and therefore the wheel B is given as great a length as is possible under the circumstances. Further, the canal S is made to have a maximum terminal area, equal to approximately one-half the circumference of the wheel B. Therefore, when the difference is slight and the quantity of water great the wheel will be rather slowly yet powerfully rotated by the water.

It will be noted than in this embodiment of my invention the turbine wheel is located with its horizontal axis in substantially the same plane as the water bed of the low pressure side C and therefore the canal S extends below this level. With this arrangement the tendency of the water passing through the canal S is to rise as soon as permissible, but of course before this can take place the wheel must be rotated by the passage of the water therethrough.

In Fig. 1 is shown a valve d which can be opened more or less to permit the head in the high pressure side T to be more or less reduced according to the power which it is desired to develop by means of the turbine wheel B.

It is desirable even in the reaction turbine above described that the water in passing through the wheel engage the blades substantially tangentially of the wheel so that the kinetic energy as well as the static energy can be utilized. For this purpose there may be provided in the canal S as shown in Fig. 3, a series of guides n which are close to the wheel and another series of guides m which are relatively short and which are in line with the guides n. The guides m are not

continuous so as to avoid the utilization merely of the kinetic energy, in other words, to permit the pressure in the various channels formed thereby to be equalized.

The turbine wheel B and the general arrangement above described may be employed to advantage for utilizing the energy of wind. Such a device is illustrated in Fig. 2. In this figure there is a funnel shaped chamber T adapted to face the direction from which the wind comes so that the wind will force the air contained in the chamber T down through an auxiliary funnel shaped conduit R to a canal S located adjacent the base of the device. The air in the conduit R under pressure due to the force of the wind on the air in the chamber T is forced through the canal S and through the blades of the turbine wheel B in the same manner as the water is forced by pressure through the turbine wheel B in the arrangement shown in Figs. 1 and 3. The air then passes through the hollow column having a chamber a and thence through a passage C. It will be understood that the air in the passage C is either at normal pressure or less than normal pressure due to the rushing of the wind past the same and drawing the air from the chamber C while the air in the chamber T is under the excess pressure of the wind. Consequently, there will be a difference in pressure of the air at opposite sides of the wheel B, and so long as this pressure is maintained the wheel will be rotated. The chamber T and chamber C are mounted upon rollers so that the chamber T will always be facing toward the direction from which the wind comes. The advantage of this form of "wind mill" is that the operated part is located near the ground thus avoiding the necessity of having driving connections from the top of the tower to the machines at the base thereof.

I claim as my invention:

1. In combination, a turbine wheel comprising a plurality of curved blades arranged in an annular series around the circumference of the wheel, the spaces between certain of the blades at one side of the wheel being in communication by a passage through the wheel with the spaces between certain of the blades at the opposite side of the wheel, a conduit for the motive fluid and in which the wheel is mounted, and means dividing the conduit into an inlet side and an outlet side, the turbine wheel being mounted in said conduit with its axis of rotation in substantially the same horizontal plane as the fluid bed at the lower pressure side.

2. A structure as set forth in claim 1 including means at the inlet side of the turbine wheel for causing the motive fluid to cover approximately one-half of the circumference of the wheel.

3. A structure as set forth in claim 1 including a canal for the motive fluid at the inlet side of the turbine wheel, said canal extending below the fluid bed at the lower pressure side.
4. An apparatus for utilizing the energy of the wind, comprising a hollow tower closed at its base and open at its top, a horizontal conduit arranged to rotate freely upon the upper end of said tower, a turbine arranged in the interior of said tower at the base thereof, means dividing said horizontal conduit into an inlet duct and an outlet

duct, and means dividing the hollow space within said tower into an inlet duct and outlet duct, the inlet duct in said tower being in communication at all times with the inlet side of the turbine and with the inlet duct of the horizontal conduit and the outlet duct in said tower being in communication at all times with the outlet side of said turbine and with the outlet duct of said horizontal conduit. 15 20

Signed at Christiania, Norway.
